APPARATUS FOR INTRODUCING FLUID INTO
SUBSURFACE FORMATIONS

Norman A. Nelson, Houston, Tex., assignor, by
mesne assignments, to Standard Oil Develop-
ment Company, Elizabeth, N. J., a corporation
of Delaware

Application December 14, 1950, Serial No. 200,769

2 Claims. (Cl. 166—1)

1

The present invention relates to the treatment of subsurface formations penetrated by a borehole. More particularly, the present invention relates to an apparatus for introducing measured quantities of a fluid into a well bore, particularly those drilled for oil and gas, through a tubing string.

In the drilling of boreholes into subsurface formations for the production of subsurface fluids, particularly oil and gas, it is common practice to introduce fluid materials of one kind or another into the borehole. Ofttimes it is desirable or necessary to deliver a known quantity of such a fluid. These materials are usually introduced into the borehole through the tubing. For example, in cementing operations, cement slurry is pumped down through the tubing string into the borehole. When it is desired to squeeze the cement into the surrounding formation or into the space between the casing and the borehole walls, the cement slurry is followed up with a non-hardening fluid such as water, pressure being supplied at the surface of the earth to the water to move the cement into the desired position. In still another instance, a resin-forming liquid is introduced into the borehole through the tubing string after which it is forced into its desired position by means of a non-hardening fluid, such as water, after which the resin-forming liquid is allowed to set to a hardened mass.

It is often desirable that the quantity of fluid introduced into the borehole through the tubing string be known with exactitude. In past field practice, this has not always been possible due to the method by which the fluid has been introduced into the borehole and also due to lack of effective means either at the surface of the earth or in the borehole for measuring volumetric quantities accurately. The inaccuracies encountered in the field are particularly exaggerated when it is attempted to introduce small quantities of fluid.

The principal object of the present invention is to provide a method and apparatus for introducing known quantities of fluid materials into boreholes drilled into subsurface formations. A further object is to provide a method and means for introducing fluids into the borehole through the tubing string.

Briefly, the present method may be described as involving the steps of introducing into the borehole a tubular sleeve having a stop therein arranged to permit the passage of fluid therethrough longitudinally of the sleeve, the sleeve being anchored against longitudinal movement

2

within the borehole. A string of tubing is lowered into the anchored sleeve until the lower end of the tubing abuts on the stop carried in the sleeve. A piston-like plug, preferably carrying a resilient sealing material on its outer cylindrical surface, is introduced into the upper end of the tubing. This plug is so designed that it can be pumped down the tubing in contact with the inner walls thereof, the outer walls of the plug forming a fluid-tight seal with the inner walls of the tubing. After the plug is introduced into the tubing, the fluid which it is desired to introduce into the borehole in measured quantity is pumped into the tubing above the plug, thus forcing the plug downwardly within the tubing. Introduction of fluid into the tubing is continued until a desired quantity has been introduced thereto or until the plug reaches the stop in the tubular sleeve, at which time another plug is introduced into the tubing. With the first plug closing off the lower end of the tubing no further quantity of fluid can be introduced into the tubing until this plug is removed. In order to accomplish rejection of this plug from the lower end of the tubing, the tubing string is raised sufficiently to permit the plug to be forced out the lower end thereof, at which time pressure is applied above the upper plug. This pressure may be exerted by pumping additional similar fluid into the tubing above the second plug or by pumping a dissimilar fluid into the tubing above the second plug, a sufficient quantity of fluid being introduced above the second plug to force the second plug downwardly in the tubing to the lower end thereof, at which time it will abut against the stop in the sleeve and close off the lower end of the tubing. With the lower end of the tubing string closed off, the pressure in the tubing builds up indicating to the operator that the plug has reached the lower end of the tubing. Thus the operator knows that all the fluid between the two plugs has been introduced into the borehole. The second plug can be forced from the lower end of the tubing by raising the tubing slightly and applying pump pressure. When the last plug has been forced out of the tubing, pressure can be applied to the fluid introduced into the borehole, if desired.

The apparatus of the present invention may be briefly described as consisting of a tubular sleeve having a stop positioned therein arranged to permit the passage of fluid therethrough longitudinally of the sleeve, a tubular member connectible with the tubing string in longitudinal alignment therewith, the tubular member being

longitudinally movable in said sleeve, and a resilient piston-like plug arranged in said tubing string for longitudinal movement within said tubular member in sealing type relation with the inner surface of the tubing string and the tubular member. The piston-like plug is arranged to close off the lower end of the tubular member when said lower end abuts against the stop in the tubular sleeve and to be ejected from the lower end of the tubular member when said tubular member is moved away from said stop.

The invention is further described herein-after and is illustrated in the accompanying drawings in which

Fig. 1 is a vertical section of one embodiment of the device of the present invention shown in operative position in a cased borehole;

Fig. 2 is a detail view of a portion of the device shown in Fig. 1;

Fig. 3 is a view taken along the line 3-3 of Fig. 2;

Fig. 4 is a fragmentary sectional view showing the operation of the plug retaining flaps of the present invention;

Fig. 5 is a vertical sectional view of another embodiment of the apparatus of the present invention;

Fig. 6 is a vertical sectional view of another embodiment of the apparatus of the present invention;

Fig. 7 is a fragmentary sectional view of another embodiment of the apparatus of the present invention;

Fig. 8 is a fragmentary sectional view of a detailed embodiment of the apparatus of Figs. 1 to 4 of the present invention; and

Fig. 9 is a top view of the perforated stop plate shown in Fig. 8.

Referring to the drawings, like numerals designate similar parts throughout. In Figs. 1, 2 and 3 the device of the present invention is designated by the letter A, the remainder of the structure being included to illustrate the manner in which said device is used and to illustrate the practice of the present invention.

Referring to Figs. 1, 2, 3 and 4, borehole 10 is drilled into the earth 11, the borehole being provided for a major portion of its extent with casing 12 cemented in place with cement 13. Attached to the top of casing 12 is a casing-head 14 which may be provided with valve connections 15 and 16, respectively, leading to the interior of the casing. The string of tubing 17 passes through casinghead 14 and extends downwardly within casing 12. If the well is under pressure, it will be necessary to provide a fluid-tight seal between tubing string 17 and casing-head 14; a blowout preventer 14' affixed to casinghead 14 and capable of closing around tubing string 17 in fluid-tight relation may be used for this purpose. Gate valve 18 is provided in tubing string 17 above casinghead 14, a clear passage being provided through gate valve 18, when the valve is open, having a diameter at least equal to the diameter of the interior of the tubing. An additional section 19 of the tubing string connects with valve 18 and extends upwardly therefrom, the upper end 20 of tubing section 19 being provided with a removable closure cap 21. The space within tubing section 19 between gate valve 18 and closure plate 21 may be regarded as a lock chamber 22. Conduit 23 controlled by valve 24 fluidly connects with chamber 22 while conduit 25 containing valve 26 also fluidly connects with chamber 22.

Conduit 27 fluidly connects valves 24 and 26 while conduit 28 containing valve 29 fluidly connects with conduit 27. An additional conduit 30 containing valve 31 also fluidly connects with chamber 22.

A sleeve member 32 is anchored within casing 11 by a suitable means as by means of slips 33. As is shown, sleeve 32 is concentrically arranged within casing 12. In the embodiment shown in Fig. 1, the lower end 34 of sleeve 32 is shown as being suspended above the bottom 35 of borehole 10, a packer 36 being provided between sleeve 32 and casing 12 to prevent the passage of fluid through the annular space between the outer surface of sleeve 32 and the inner surface of casing 12.

The upper end 37 of sleeve 32 is closed by means of closure cap 38 which defines a central opening 39 extending through said cap. An annular recess 40 opens into opening 39, a suitable sealing means 41, such as an O-ring, being positioned within annular recess 40.

Disposed within sleeve 32 is a transversely extending stop 42 affixed at its outer periphery to the inner surface 49 of sleeve 32, said stop defining a plurality of passages 43 adjacent its outer periphery and a centrally disposed passageway 42'. Perforated sleeve 44 is arranged concentrically within sleeve 32, the upper end 45 of sleeve 44 abutting against the lower surface 46 of cap 38 and the lower end 47 of perforated sleeve 44 abutting against stop 42 and being secured thereto. Openings 43 in stop 42 allow fluids to move longitudinally within sleeve 32 between the annular space formed by the outer surface 48 of perforated sleeve 44 and the inner surface 49 of sleeve 32 and the space 50 within sleeve 32 below stop 42.

Tubular member 51 is threadedly engaged at its upper end 52 with tubing string 17, the lower end 53 of tubular member 51 defining a plurality of radially extending projections 54 which fit slidably within grooves 54' which extend longitudinally of perforated screen 44. Tubular member 51 is arranged to move slidably through opening 39 of closure plate 38, sealing means 41 providing a fluid-tight seal between the outer surface of tubular member 51 and closure plate 38. Projections 54 abut on the under side 46 of closure plate 38 when tubular member 51 is raised within sleeve 32, thereby limiting the upward movement of tubular member 51 with respect to sleeve 32. In Fig. 1 the lower end 53 of tubular member 51 is shown as abutting against stop 42. A resilient piston-like plug 56 is disposed inside tubular member 51, the outer cylindrical surface of said plug being in fluid-tight relation with the inner surface of said tubular member, the lowermost face 57 of plug 56 being in contact with stop 42.

A plurality of plug retainer flaps 60 are positioned in openings 60' of perforated sleeve 44. Flaps 60 are pivotally connected at their upper end to sleeve 44 by pins 61 and their lower end 65 is biased inwardly by spring 67. Flaps 60 are radially spaced from the longitudinally extending grooves 54'. The function of flaps 60 is to prevent the re-entrance of resilient piston-like plug 56 into the interior of tubular member 51 after the plug has been ejected therefrom and after tubular member 51 has been raised within perforated sleeve 44 so that outwardly extending projections 54 abut against closure plate 38. Thus, each of flaps 60 is pressed by spring 67 through an opening forcing the lower edge 65 thereof into contact with the outer surface of tubular member 51 along which the flap normal-

ly rides. However, when tubular member 51 is raised within sleeve 32 until outwardly extending projections 54 abut against the under side 46 of closure plate 38, the lower edge 65 of flaps 60 cease to ride on the outer surface of tubular member 51, at which time lower edge 65 extends even further into perforated sleeve 44, all of said flaps cooperating to form a barrier against upward movement of piston-like plug 56 therewith. Flaps 60 are shown most clearly in their plug retaining position in Fig. 4.

Having fully described the embodiment shown in Figs. 1, 2, 3 and 4, its operation will now be described. Cap 21 affixed to tubing extension 19 is removed and a piston-like plug 56 is introduced into chamber 22 after which closure plate 21 is again secured to tubular extension 19. During the introduction of plug 56 into chamber 22, gate valve 18 and valve 29 are closed and valve 31 is opened, valve 31 being in the open position; any fluid trapped in chamber 22 may thus escape therefrom. After plug 56 has been introduced into chamber 22, valves 31 and 26 are closed and valves 18, 24, and 29 are opened. The fluid material which is to be delivered to borehole 10 in definite volume is introduced into tubing 17 and tubular member 51 by pumping the fluid into chamber 22 above plug 56 through conduit 28 controlled by valve 29. The introduction of fluid into chamber 22 above plug 56 causes, of course, plug 56 to descend within tubing 17. After the desired quantity of fluid has been introduced into chamber 22, gate valve 18 and valve 29 are closed, closure plate 21 removed, and a second resilient plug 56' is inserted into chamber 22 in the same manner as the first plug 56 was introduced. Closure plate 21 is then replaced and gate valve 18 and valves 24 and 29 are opened. A fluid, which may be a fluid similar to that previously introduced or dissimilar to that previously introduced, is then introduced into chamber 22 through conduits 28, 27, and 24. Pump pressure may be indicated by a suitable gauge and pumping of this fluid is continued until the gauge registers a sudden large increase in pressure. This sudden increase in pressure will occur when plug 56 strikes stop 42 inasmuch as the lower end 53 of tubular member 51 is abutting on stop 42 during this pumping operation. At this stage the operator knows that the measured quantity of fluid in tubing 17 and tubular member 51 is now ready to be delivered to the borehole. Delivery of this fluid into the borehole is accomplished by raising tubing 17 and tubular member 51 a sufficient amount to permit plug 56 to be forced from the lower end 53 of tubular member 51, thereby permitting the fluid above this plug to escape from the lower end of said tubular member. The operator will know when plug 56 has been expelled from the lower end 53 of tubular member 51 because the pump pressure will decrease when this occurs. The pipe 51 is raised only enough to allow the plug 56 to be ejected. The plug, however, remains below the lower end of pipe 51 in position to form a stop for the next plug 56. The fluid material flowing from the lower end 53 of tubular member 51 will pass through the perforations defined by perforated sleeve 44 into the annular space between the perforated sleeve and outer sleeve 32 through openings 43 defined by stop 42 into space 50 and thence into borehole 10. Fluid will continue to flow from the lower end 53 of tubular member 51 until the second resilient plug 56'.

strikes the first resilient plug 56, at which time further downward movement is prevented and fluid ceases to flow downwardly within tubing 17. The lower end 53 of tubular member 51 is now closed by the second resilient plug 56', a condition which is announced to the operator by the increase in pump pressure. This increase in the pump pressure signifies to the operator that all of the fluid between the first and second resilient plugs has been introduced into borehole 10.

Fluid in tubing 17 above the second resilient plug 56', whether it be a fluid similar to the fluid between the first and second plugs or a fluid dissimilar to the fluid between the first and second plugs, can now be delivered to the borehole by the operator if he so desires. If he desires to squeeze the fluid material formerly positioned between the first and second plugs into formation 10', a quantity of driving material, such as water, may be introduced through tubing string 17 into borehole 10 for accomplishing this objective. If it is desired to introduce a definite quantity of the driving fluid, its volume may also be measured in the manner hereinbefore described.

If after introducing a quantity of fluid material, it is desired to remove the device of the present invention from the borehole, slips 33 and packer 36 are disengaged from casing 12. Tubing 17 is then raised which will, in turn, cause tubular member 51 to move upwardly within sleeve 32 until projections 54 abut against closure cap 38 at which time flaps 60 will pivot about pins 61, the lower edge 65 of flaps 60 projecting into the interior of perforated screen 44. If it is desired to reverse circulate, as by pumping a fluid such as drilling mud into the annular space between tubing 17 and casing 12 through conduits 15 or 16, the fluid so circulated will pass from said annular space into the interior of sleeve 32, thence through openings 43 in stop 42 and through the perforations of sleeve 44 into the interior thereof. Since the direction of flow is upward within perforated sleeve 44, resilient plugs 56 within said sleeve will tend to move upwardly but their upward movement will be limited by abutment against flaps 60. Since flaps 60 limit the upward movement of resilient plugs 56, the fluid being reverse circulated can flow from the annular space between perforated sleeve 44 and sleeve 32 through the perforations of sleeve 44 located below flaps 60 and thence into tubing 17. After reverse circulation is completed, further raising of tubing 17 lifts the device of the present invention and such lifting may be continued until said device is raised through blow-out preventer 14' and clear of the well head.

A more simplified form of the apparatus of the present invention than that shown in Fig. 1 is illustrated in Fig. 5. Referring to Fig. 5, a well bore 10 is drilled into the earth 11, borehole 10 being provided with casing 12 down to a point in borehole 10 above subsurface formation 10'. Casing 12 is shown as cemented in place with cement 13. Attached to the top of casing 12 is a casinghead 14 having valved connections 15 and 16, respectively, leading to the interior of the casing. Affixed to casinghead 14 is a blow-out preventer 14'. A string of tubing 17 extends through casinghead 14 and blow-out preventer 14' into casing 12, tubing string 17 being arranged to be moved longitudinally in casing 12 through casinghead 14 and blow-out

preventer 14' in fluid-tight relation with blow-out preventer 14'. Tubing string 17, above blow-out preventer 14', is provided with a gate valve 18, gate valve 18 having a clear passage therethrough when the valve is open, the passage 5 having a diameter at least equal to that of the internal diameter of the tubing. An extension 19 of tubing 17 connects with gate valve 18, the upper end 20 of extension 19 being provided with a removable closure plate 21. The space inside extension 19 between gate valve 18 and removable closure cap 21 will hereinafter be designated as lock chamber 22. Conduit 23 containing valve 24 and conduit 25 containing valve 26 connect with chamber 22. Conduit 27 joins conduit 23, 15 and conduit 25 and conduit 28 containing valve 29 connect with conduit 27. Conduit 28 is connectible to pumps for supplying fluids to be introduced into chamber 22. Conduit 30 containing valve 31 also connects with chamber 22 and may be used as a drain line for said chamber if desired.

A plug stop 70 in the form of a disc or plate having a plurality of openings 71 positioned adjacent its outer periphery and a centrally disposed opening 70' is removably secured to casing 12, as by means of a suitable slip assembly 72. It will be noted that plug stop 70 extends across the bore of casing 12 and is substantially perpendicular to the longitudinal axis of said casing.

When it is desired to introduce a measured quantity of a given fluid into the borehole when using the embodiment illustrated in Fig. 5, and assuming that borehole 10 already contains a different fluid, gate valve 18 is closed and valve 31 is opened, permitting fluid to drain from chamber 22 through conduit 30. After chamber 22 has been drained through conduit 30, valve 31 is closed and removable closure plate 21 is removed from the upper end 20 of extension 19. A resilient piston-like plug is introduced into chamber 20, it being pushed into said chamber until its upper edge is below the point at which conduit 23 connects with chamber 22. The introduction of the measured quantity of fluid to be introduced into the borehole is then commenced by pumping said fluid through conduit 28, conduit 27, and conduit 23, valves 29 and 24 being opened and valve 26 being closed during this initial pumping operation. When sufficient fluid has been introduced into chamber 22 to force the piston-like plug against the upper edge of gate valve 18, this valve is opened to permit passage of said plug therethrough. The introduction of fluid is continued until the desired quantity has been introduced into tubing 17, at which time pumping is discontinued and valve 29 and 24 are closed. Valve 18 is also closed. Valve 31 is opened to permit fluid to drain from chamber 22, after which valve 31 is closed and plate 21 again removed from the upper end 20 of extension 19. A second resilient plug is then introduced into said chamber and is pushed downwardly therein until its lower edge contacts the upper surface of the fluid previously introduced into chamber 22, this upper surface, of course, being on a level with conduit 30. Closure plate 21 is again secured to the upper end 20 of extension 19 and additional fluid, either similar to the fluid previously introduced or dissimilar from said fluid, the choice being with the operator, is introduced into chamber 22 above the piston-like plug through conduits 28, 27, and 23, valves 24 and 29 be-

ing opened and valve 26 being closed. When the piston-like plug abuts against valve 18, this valve is opened, permitting the piston-like plug to pass therethrough. If it is desired that the fluid introduced behind the second plug also be introduced in measured quantity and that it be separated from a subsequent slug of fluid, a third piston-like plug may be employed to divide the second and third batches of fluid. It will be understood, of course, that as many different segregated batches of fluid as desired may be introduced into tubing string 17. In the drawing, the batches are shown as being separated by plugs 73, 73', and 73''. It will be understood, of course, that as soon as plug 73 is started downwardly in tubing string 17 by the fluid pressure exerted thereabove, the fluid already present in the borehole will be displaced from borehole 10 by the introduced fluid. The displaced fluid can either be forced into formation 10' ahead of the introduced fluid by maintaining valved conduits 15 and 16 closed or it may be permitted to flow upwardly through the annular space between tubing 17 and casing 12 and outwardly of the casing through valve conduits 15 or 16 or both. Fluid introduced under pressure through conduit 28 will continue to force piston-like plugs 73, 73', and 73'' downwardly within tubing 17 until the lowermost of these plugs, namely 73, abuts on plug stop 70. Since the lower edge 17' of tubing string 17 also abuts on plug stop 70, the arrival of piston-like plug 73 at stop 70 effectively prevents further movement of fluid within tubing 17. This, of course, causes an increase in pressure in tubing 17, this increase in pressure indicating to the operator that plug 73 has reached stop 70. After noting this increase, the operator then raises tubing string 17 a sufficient amount to permit plug 73 to be forced out the lower end 17' of tubing 17, at which time the fluid inside tubing 17 can flow out the lower end 17' of said tubing through openings 71 in plug stop 70 into borehole 10. Normal pumping is continued until piston-like plug 73' reaches the lower end 17' of tubing 17, at which time piston-like plug 73' abuts against piston-like plug 73, preventing further movement of fluid through tubing 17 and causing another increase in pressure. This increase is noted by the operator who again lifts tubing 17 until plug 73' is forced out the lower end 17' of tubing 17. With piston-like plug 73' forced out the lower end 17' of tubing 17, normal pumping can again be resumed, if desired, to deliver the batch of fluid between piston-like plug 73' and piston-like plug 73''. This alternate pumping and lifting can be repeated by the operator as many times as is desired until all the introduced plugs have been forced to the lower end 17' of tubing 17.

Another embodiment of the apparatus of the present invention is shown in Fig. 6. Referring to Fig. 6, a well bore 10 is drilled into the earth 11, borehole 10 being provided with casing 12 down to a point in borehole 10 above subsurface formation 10'. Casing 12 is shown as cemented in place with cement 13. The surface equipment attached to the top of casing 12 is not shown as it is the same as that shown in the previous figures.

A tubing sleeve 100 is arranged concentrically within borehole 10, its upper end 101 being suspended from and secured to casing 12 by means of slips 102. A packer 103 is also provided, the packer closing off the annular space between

sleeve 100 and casing 12. The open lower end 104 of tubular member 100 is suspended off the bottom 35 of borehole 10. A plug stop 105 is secured within tubular member 101, plug stop 105 being provided with a plurality of openings 106 adjacent its outer periphery and a centrally disposed passageway 105'. Plugs 107 and 108 are disposed within tubing 17. Plugs 107 and 108 are longitudinally movable within tubing string 17 in sliding and sealing contact with the inner walls thereof.

When it is desired to introduce a known quantity of fluid into the borehole with the embodiment shown in Fig. 6, and assuming the borehole contains another fluid, such as water, valve conduits 15 and 16 are closed off and plug 107 is inserted in tubing string 17. The fluid to be introduced is then pumped into tubing 17 above plug 107 and plug 107 forced downwardly therein. When the desired quantity of fluid has been introduced into tubing 17 above plug 107, plug 108 is then inserted and additional fluid introduced above plug 108. The fluid introduced above plug 108 may be a fluid similar to that introduced between plugs 107 and 108 or it may be a different fluid. In any event, in order to deliver the fluid in tubing 17 located between plugs 107 and 108, fluid is introduced into tubing 17 under pump pressure until plug 107 reaches the lower end 109 of tubing 17, said lower end 109 abutting on plug stop 105. When plug 107 reaches the lower end 109 of tubing 17, it also abuts on stop 105, preventing further movement of fluid within tubing 17. This causes a build-up of pressure in tubing 17, this build-up of pressure indicating to the operator that plug 107 has reached the lower end 109 of tubing 17. At this stage the operator raises tubing 17 until plug 107 is expelled from the lower end 109 thereof, permitting fluid to flow from the interior of tubing 17 through openings 106 and out the lower end 104 of tubular member 100 into borehole 10. Fluid will continue to flow from tubing 17 until such time as plug 108 reaches the lower end 109 of said tubing, at which time plug 108 will abut against the upper edge 110 of plug 107. Again the pump pressure will build up and indicate to the operator that plug 108 has reached the lower end of tubing 17. It will further indicate to the operator that all of the fluid in tubing 17 between plugs 107 and 108 has been delivered to borehole 10. If the operator desires to deliver additional fluid to borehole 10, tubing 17 is again raised and pump pressure applied within tubing 17 to expel plug 108 from the lower end thereof.

A variation of the embodiment of Fig. 6 is illustrated in Fig. 7. The only difference in the structure of Fig. 6 and that of Fig. 7 is that the necessity for providing a packer or slips, or both, is eliminated.

Referring to Fig. 7, a well bore 10 is drilled into the earth 11, borehole 10 being provided with casing 12 down to a point in borehole 10 above subsurface formation 10'. Casing 12 is shown as cemented in place with cement 13. A tubular member 120 is lowered within casing 12 and set in position within borehole 10 with its upper end 121 being positioned above the lower terminus of casing 12. The lower end 122 of tubular member 120 rests on bottom 35 of borehole 10. Disposed within tubular member 120 is a plug stop 123 which defines a plurality of openings 124 adjacent the outer periphery thereof and a centrally disposed passageway 123'. Below stop 123 and above the lower end 122 of tubular member 120, said tu-

bular member is provided with perforations 125 for the passage of fluids therethrough. Tubing string 17 extends from the surface of the earth into tubular member 120, its lower edge 126 abutting on plug stop 123.

The manner in which the embodiment of Fig. 7 operates is identical with the manner in which the embodiment of Fig. 6 operates except for the fact that fluid introduced through tubing 17 instead of flowing around the lower edge 122 of tubular member 120, as it does in the embodiment of Fig. 6, flows through perforations 125.

The device illustrated in Figs. 8 and 9 is identical with that shown in Figs. 1, 2, 3 and 4 except for the design of the plug stop. Referring to Figs. 8 and 9, borehole 10 is provided with casing 12 cemented in place by means of cement 13. Tubular member 32 is secured in place within casing 12 by means of slips 33 and packer 36. A plug stop 130 is secured within sleeve 32, plug stop 130 being provided with a plurality of openings 131 adjacent the outer periphery thereof. A central opening 132 extends through plug stop 130. Perforated sleeve 44 is disposed within sleeve 32 with its lower edge 47 abutting on plug stop 130. As will be noted in Fig. 8, the diameter of opening 132 is less than the internal diameter of sleeve 44. The purpose of providing opening 132 in plug stop 130 is to permit the passage of the balls therethrough, not shown, needed for setting certain well-known commercial packers and slips. After these balls have been passed by plug stop 130 and such packers and slips have been set, a larger ball is introduced, this larger ball being of such size that it will not pass through opening 132. This ball, designated 133, is also of a material which is sufficiently resilient to close off opening 132 and to prevent the passage of fluid therethrough. When ball 133 is used, the first piston-like plug introduced will of course abut against this ball rather than against plug stop 130.

Having fully described the apparatus and method of the present invention, what I wish to claim as new and useful and to secure by Letters Patent is:

1. A device for spotting a fluid material in a well comprising an outer sleeve, a horizontally disposed stop in said sleeve having at least a port adjacent an outer periphery of the stop and a second port in said stop centrally disposed therein for the passage of fluid therethrough, an inner perforated sleeve concentrically arranged within said outer sleeve to form an annular space between the outer surface of the perforated sleeve and the inner surface of said outer sleeve communicating with said port, the upper end of said perforated sleeve and the upper end of said outer sleeve being joined in fluid-tight relation, the lower end of said perforated sleeve abutting against said stop, and a tubular member adapted to be connected at its upper end to a tubing string, said tubular member being slidably arranged in said perforated sleeve for longitudinal movement therein, said tubular member and tubing containing at least one plug slidably arranged therein in fluid-tight relation with the inner surface of said tubular member and tubing.

2. A device for spotting a fluid material in a well comprising an outer sleeve, a perforated circular plate arranged horizontally in said sleeve having a plurality of ports adjacent an outer periphery of the plate and a second port in said stop centrally disposed therein for passage of fluid therethrough, an inner perforated sleeve concentrically arranged within said outer sleeve to

11

form an annular space between the outer surface of the perforated sleeve and the inner surface of the outer sleeve communicating with said ports, the upper end of said perforated sleeve and the upper end of said outer sleeve being joined in fluid-tight relation, the lower end of said perforated sleeve abutting against said plate, and a tubular member defining a lateral stop member with a lower end thereof adapted to be connected at its upper end to a tubing string, said 10 tubular member being slidably arranged in said perforated sleeve for longitudinal movement therein, said tubular member and tubing containing at least one plug slidably arranged there-

12

in in fluid-tight relation with the inner surface of said tubular member and tubing.

NORMAN A. NELSON.
